UNITED STATES PATENT OFFICE.

EDWARD J. BARCALO, OF BUFFALO, NEW YORK,

DESIGN FOR A FRAME FOR BED ENDS.

SPECIFICATION forming part of Design No. 32,410, dated March 27, 1900.

Application filed February 26, 1900. Serial No. 6,648. Term of patent 7 years.

To all whom it may concern:

Be it known that I, EDWARD J. BARCALO, a citizen of the United States, residing at Buffalo, in the county of Erie and State of New York, have invented and produced a new and original Design for Frames of Bed Ends, of which the following is a specification, reference being had to the accompanying drawing, forming a part thereof.

10 This design relates to the configuration of the frame of a bed end.

The accompanying drawing is an elevation of a frame embodying my design.

15 As shown in the drawing, the characteristic feature of my design consists of two vertical pillars or members A A, a transverse or horizontal base member B, and curved portions C C, connecting the ends of said transverse member with the lower ends of said up-

right members and forming with said vertical and horizontal members a substantially U-shaped frame.

20 E are feet which extend downwardly from the outer or convex sides of the curved portions C of the frame.

25 Each of the pillars A is surmounted by an ornamental mount F.

g are mounts or ornaments arranged at intervals on the pillars.

What I claim is—

30 The design for the frame of a bed end, substantially as herein shown and described.

Witness my hand this 23d day of February, 1900.

EDWARD J. BARCALO.
